UNITED STATES PATENT OFFICE

110,182

DESIGN FOR A SHOE

David Levin, New York, N. Y., assignor to Avon
Shoe Co., New York, N. Y.

Application May 11, 1938, Serial No. 77,101

Term of patent 3½ years

To all whom it may concern:

Be it known that I, David Levin, a citizen of the United States of America, residing in city of New York, county of New York, and State of New York, have invented a new, original, and ornamental Design for a Shoe, of which the following is a specification, reference being had to the accompanying drawing, forming part thereof.

Fig. 1 is a plan view of a shoe, showing my new design.

Fig. 2 is a side elevational view thereof.

Fig. 3 is a fragmentary view of a portion of the vamp immediately above the shoe sole.

The shoe upper is slit through and turned back showing the lining which is of a contrasting color.

I claim:

The ornamental design for a shoe, substantially as shown and described.

DAVID LEVIN.
